NONGLARE FLASHLIGHT

George H. Seal, Glendale, Calif.

Application February 2, 1942, Serial No. 429,172

3 Claims. (Cl. 240—10.6)

This invention relates to a non-glare flashlight.

The general object of the invention is to provide a portable flashlight which includes a battery, switch, bulb and reflector and wherein novel means is provided for directing the light from the reflector so that glare is reduced.

A more specific object of the invention is to provide a flashlight body having a novel non-glare light directing member on the front thereof.

A further object of the invention is to provide an improved non-glare assembly member adapted for use in a flashlight.

A further object of the invention is to provide a novel louvre member particularly adapted for use in a flashlight.

Another object of the invention is to provide a novel combined louvre and lens member for use in a flashlight.

A further object of the invention is to provide a novel means for aligning a louvre member on a flashlight.

Other objects and advantages of the invention will be apparent from the following description taken in connection with the accompanying drawing, wherein:

Fig. 1 is a side elevation of a flashlight embodying the features of my invention;

Fig. 2 is a side elevation of the non-glare assembly member;

Fig. 3 is a front elevation of the assembly member;

Fig. 4 is an enlarged section taken on line 4—4, Fig. 3 showing the assembly member and showing a portion of the flashlight body;

Fig. 5 is a fragmentary enlarged detail showing a portion of the non-glare assembly member;

Fig. 6 is a fragmentary top plan view showing the front portion of the flashlight;

Fig. 7 is a view similar to Fig. 2 showing a modification;

Fig. 8 is a view similar to Fig. 4 showing the modification; and

Fig. 9 is a view similar to Fig. 5 showing the modification.

Referring to the drawing by reference character I have shown my invention as embodies in a flashlight which is indicated generally at 10. As shown the flashlight includes a hollow body 11 which may be made of suitable material such as metal and which may include suitable batteries 12 and a switch mechanism 13. The flashlight also includes a front member indicated generally at 14 which comprises a sub-assembly member of such nature that it can be made and assembled and may be shipped independently of the body if desired.

The member 14 includes a tubular portion 15 having an inwardly directed flange 16 at the front end thereof. At the rear end the tubular member 15 includes threads 17 and a peripheral

bead arranged adjacent to and in advance of the threads 17. The member 15 further includes a shoulder 18 adjacent to and in front of the bead 18.

Within the member 15 I arrange a front transparent closure member 20 which engages the flange 16. Also within the tubular member 15 I arrange a ring 21 which constitutes a part of the louvre member. The ring 21 engages the rear face of the transparent member 20. The ring 21 includes a plurality of parallel rearwardly directed louvre blades 22 which are secured to the ring. The ring 21 and the blades 22 may be made of suitable material such as "Bakelite" or other plastic material, or they may be made of metal and soldered or welded together.

In the rear of the louvre blades 22 I show a light deflecting lens 23. This lens includes a planar rear face 24 and a front face provided with a plurality of rib-like parallel lens members 25. A groove 26 is formed between each pair of lens members 25 and the free ends of the louvre blades 22 fit in the grooves 26 so that movement of the blades is prevented. The lens ribs 25 are of such configuration that each rib directs the light passing therethrough forwardly and convergingly with the focus disposed at 27 just in the rear of the transparent member 20. Beyond the member 20 the light beams diverge.

Light is supplied by a bulb 28 shown as mounted in a socket 29. The front end of the bulb is opaque as at 30 so that light passing from the filament 31 of the bulb impinges on a reflector 32 in which the socket 29 is mounted. Light from the reflector 32 passes through the deflecting lens 23 as described.

At the rear of the lens member 23, I arrange a gasket 33 and the gasket is engaged by a split ring 34 which fits in the bead 18 previously described. As shown in Fig. 5, the split ring 34 is arcuate in cross section and engages a peripheral flange 35 on the reflector 32 and serves to hold the latter in place. The reflector 32 is engaged by a contact member 36 mounted in the body 11 and insulated from the body by an insulating strip 37.

The switch 13 and its construction and operation form no part of the present invention and a detailed description of the switch and the wiring arrangement is believed to be unnecessary.

In order to prevent rotation of the louvre member relative to the tubular portion 15, I provide the ring 21 with a notch indicated at 38 in Fig. 5, while the tubular member is provided with a corrugation 39 which enters the notch 38 when the parts are properly aligned. To center the tubular member 15 on the body 11 so that the switch 13 will be directed upwardly when the louvres are horizontal, I show the tubular member 15 as provided with a tongue 40 which ex-

tends beyond the thread 17. This tongue is resilient and is adapted to pass over beads 41 on the body 11 while the member 15 is being screwed onto the member 11. When in fully engaged position, the tongue 40 will be disposed between the beads 41 as shown in Fig. 6 so that the parts will remain in the correct position.

In assembling the flashlight, the body 11 is made and the sub-assembly member 14 is made independently of the body and the two parts are then connected together as described. In operation when the bulb 28 is illuminated, light passes from this bulb and strikes the reflector 32 whence the beams pass through the deflecting lens 23 and between the louvre blades 22 and out through the transparent member 20. The ring 21, blades 22 and interior of the forward portion of the tubular member 15 are blacked so that they will not reflect light.

The light passing from the flashlight is directed straight ahead and there are no upwardly directed rays which produce a glare. This absence of upwardly directed rays makes my light particularly useful for "blackout" purposes so that it is of value to the military and naval forces as well as to police authorities, and is of course useful for civilians.

In Figs. 7, 8 and 9 I show a modification of my invention wherein a tubular member 50 is employed. This tubular member includes a front flange 51, a transparent member 52, a louvre ring 53 and louvre blades 54 similar to the corresponding parts previously described. The tubular member is also provided with a corrugation 54' which fits in a notch 55 and the ring 53 to center the parts. In the modification a deflecting lens 56 is provided and includes rib lens members 57 with a groove 58 therebetween in which the free ends of the blades 54 are seated.

The lens 56 in the modification engages a shoulder 59 on the tubular member 50 and is held on the tubular member by the inturned flange 60. The member 50 is shown as mounted on a flashlight body member 62. A reflector is indicated at 63 and includes a flange 64 which engages the end of the body 62. The body 62 is threaded as at 65 and the threads 65 are engaged by threads 66 on a collar 67 which has an end flange 68 which engages the shoulder 59 on the tubular member 50.

The member 50 forms a sub-assembly unit which is arranged upon the flange 64 of the reflector 63 when the latter is seated on the end of the body 62. The collar 67 is then screwed into place so that its flange 68 engages the shoulder 59 and serves to hold the parts assembled.

It is to be noted that the rays A passing from the reflector are parallel and that the rays do not touch the parallel louvre blades after passing through the deflecting lens 23.

From the foregoing description, it will be apparent that I have invented a novel non-glare flashlight which can be economically manufactured and assembled and which is highly efficient for its intended purpose.

Having thus described my invention, I claim:

1. In a flashlight, a hollow body having a threaded front end, a tubular member having an inwardly directed flange at the front end and having an enlarged threaded portion at the rear end engaging said body threaded portion, an annular bead at the inner end of the threaded portion, a shoulder adjacent to the inner end of said bead, a transparent disc closure member in said

tubular member and engaging said flange, a louvre member including an annular ring engaging said transparent member, means to prevent rotation of said ring relative to the tubular member, a plurality of parallel louvre blades secured at their front edges to said ring and extending rearwardly therefrom, the rear ends of said blades being coplanar, a light deflecting lens adjacent said tubular member shoulder and comprising a transparent disc having a planar rear face and having a plurality of light transmitting ribs on the front face thereof, said deflecting lens having a groove between each pair of ribs, the blades of said louvre having their ends each engaging in a groove on the deflecting lens, a reflector in said tubular member, a split ring engaging the periphery of said reflector, said split ring being seated in said bead, a gasket engaging said split ring, said deflecting lens engaging said gasket, a bulb mounted on said reflector, said body and tubular member threaded portion having interengaging portions to hold said tubular portions against free rotation on the body.

2. In a flashlight sub-assembly, a tubular member having an inwardly directed flange at the front end and having an enlarged threaded portion at the rear end, an annular bead at the inner end of the threaded portion, a shoulder adjacent to the inner end of said bead, a transparent disc closure member in said tubular member and engaging said flange, a louvre member having an annular ring engaging said transparent member, means to prevent rotation of said ring relative to the tubular member, a plurality of parallel louvre blades secured at their front edges to said ring and extending rearwardly therefrom, the rear ends of said blades being coplanar, a light deflecting lens adjacent said tubular member shoulder and comprising a transparent disc having a planar rear face and having a plurality of light transmitting ribs on the front face thereof, a reflector in said tubular member, and a bulb mounted on said reflector.

3. In a flashlight, a hollow body having a threaded front end, a tubular member having an inwardly directed flange at the front end and having an enlarged threaded portion at the rear end engaging said body threaded portion, a transparent disc closure member in said tubular member and engaging said flange, a louvre member including an annular ring engaging said transparent member, a plurality of parallel louvre blades secured at their front edges to said ring extending rearwardly therefrom, the interior of the forward end of the tubular member and the surface of said blades being non-reflecting, the rear ends of said blades being coplanar, a light deflecting lens comprising a transparent disc having a planar rear face and having a plurality of light transmitting ribs on the front face thereof, each rib having a configuration to direct light rays convergingly forward to a focus midway between the adjacent louvres and just in the rear of the transparent closure, there being a groove between each pair of ribs, the blades being arranged parallel to the axis of the tubular member, the blades of said louvres having their ends releasably engaging in one of the grooves on the deflecting lens, a reflector in said tubular member, a bulb in said reflector, means to hold said louvre member against rotation on the tubular member and means to hold said tubular member against rotation on the body.
